(57) **CLAIM**

The ornamental design for a film applicator, as shown and described.

DESCRIPTION

FIG. 1 is a front; bottom and right side perspective view of a film applicator, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The product is device for screen protector for cell phone or ipad.

The broken lines in the drawings illustrate the portions of the film applicator, which form no part of the claimed design.
